F. MEYER

HOLDER FOR ARC LAMP CARBONS

Filed Feb. 8, 1928

Fig.1

Fig. 2

Inventor:

Franz Meyer

UNITED STATES PATENT OFFICE.

FRANZ MEYER, OF JENA, GERMANY, ASSIGNOR TO THE FIRM CARL ZEISE, OF JENA, GERMANY.

HOLDER FOR ARC-LAMP CARBONS.

Application filed February 8, 1928, Serial No. 252,910, and in Germany February 21, 1927.

The present invention relates to a holder for arc lamp-carbons in which the carbons are moved by means of a chain. According to the invention the chain is guided in a groove of the holder in such a way that, even if pushed, it cannot deflect laterally. One attains in this way a moving organ for the carbon which admits of actuating the latter from a stationary part of the holder in both a forward and backward direction, even if the carbon be carried by a part, which is movable relatively to the stationary one, e. g. a more or less inclinable part without the necessity, as for instance with the use of a closed chain, of guiding the chain as far as the burning end of the carbon and to provide there a guide-member for the chain, e. g. a loose roller.

In the annexed drawing Fig. 1 shows a constructional example of the invention in a side elevation, partly in a section; Fig. 2 is a section along the line 2—2 of Fig. 1.

The carbon-holder shown consists of two parts a^1 and a^2 , of which the former is to be fixed on the casing of the arc lamp. Both parts are coupled to each other by means of a joint a^3 and a support b^1 , variable in its length with the aid of a screw b . At the upper end of the part a^2 is fixed a cylindrical guide piece c for a carbon d , which is held at its rear end by a clamp e , guided in a groove f^2 of the part A^2 . The part a^1 is provided with a groove f^1 , corresponding to the groove f^2 , and in the grooves of both parts is guided a link chain g since the outer link-plates, lying on the side of the parts a^1 and a^2 , slide in the grooves f^1 and f^2 . Some of the link-bolts are constructed as elongated bolts g^2 , which pass through the grooves f^1 and f^2 and bear with a head g^3 against the back of the parts a^1 and a^2 . At its upper end this chain is connected to the

clamp e . At the bottom end of the chain g is fixed a rack g^1 , engaging in a pinion h . By means of a pair of bevel wheels i^1 , i^2 this pinion is connected to a regulating motor by which the pinion may be rotated according to requirements in the one or the other direction.

As may be seen, the inclination of the part of the holder a^2 may be displaced and in each position the open chain g may be moved from its bottom end in both a forward and backward direction.

I claim:

1. A holder for the one of the carbons of an arc lamp, comprising a carrier adapted to be fixed on the casing of the arc lamp and provided with a groove, a sliding piece displaceably supported on this carrier, means for fixing a carbon on this sliding piece, a chain fixed with its one end on this sliding piece and guided in the said groove, a device for displacing the chain, and means connecting this device to the other end of the chain. 55

2. In a holder according to claim 1, the chain being a link chain.

3. A holder for the one of the carbons of an arc lamp, comprising a carrier adapted to be fixed on the casing of the arc lamp and provided with a groove, the carrier consisting of two parts inclined at an angle relatively to each other, a link connecting the two parts of the carrier to each other, a contrivance for displacing the said angle, a sliding piece displaceably supported on this carrier, means for fixing a carbon on this sliding piece, a chain fixed with its one end on this sliding piece and guided in the said groove, a device for displacing the chain, and means connecting this device to the other end of the chain. 75

FRANZ MEYER.
